UNITED STATES PATENT OFFICE.

RAYMOND C. MOTT AND JESSE ALEXANDER, OF CLINTON, INDIANA.

HAY-PRESS.

1,221,573.

Specification of Letters Patent. Patented Apr. 3, 1917.

Application filed September 23, 1912. Serial No. 721,933.

To all whom it may concern:

Be it known that we, RAYMOND C. MOTT and JESSE ALEXANDER, citizens of the United States, residing at Clinton, in the county 5 of Vermilion and State of Indiana, have invented a new and useful Hay-Press, of which the following is a specification.

Our invention relates particularly to motor-driven hay-presses of the gasoline engine 10 type, and its particular objects are: first; to provide a simplified type of transmission from the gasoline engine for actuating the hay-press, which shall cost less to construct and have a minimized liability to get out 15 of order; second; to furnish a means of quick-return for the hay-press plunger which shall increase the output of the press by doubling the frequency with which bales may be taken from it; third; to furnish a 20 type of construction which shall be capable of being equally well operated by horse power draft in the event of exhaustion of fuel or accident to the engine.

We attain the objects stated by means of 25 the construction illustrated in the accompanying drawings, in which—

Figure 1 is a side elevation of our hay-press, with a small portion of the compress screw casing and baling chamber broken 30 away to show the construction; Fig. 2 is an enlarged top plan of the engine bed with its concentrically inclosed turntable; Fig. 3 is an enlarged vertical section taken on the motor end of our hay-press and the details 35 of its transmission gear mechanism; Fig. 4 is an enlarged sectional plan of the engine bed with its inclosed turntable taken upon the line 4—4, Fig. 3, showing the arrangement of the quick-return gear train, said 40 view being taken on the section line 3—3 of Fig. 2; Fig. 5 is an enlarged sectional plan of the engine bed with its inclosed turntable, taken upon the line 5—5, Fig. 3, showing 45 the pressure gear train; and Fig. 6 is a much enlarged detail, showing the gears.

Similar numerals refer to similar parts throughout the several views.

Referring to Fig. 1, the separable truck frame 1 has its lap joints 2 united by bolts 50 3 in the customary manner and is supported upon the truck 4 with its draft-pole 5 and vertically adjustable follower truck 6 in the usual manner. Bolts 7 superiorly secure upon the rear end of said truck frame 1 the 55 hay-press frame 8, having built thereon the baling chamber 9, surmounted by the hay

hopper 10, for feeding the hay to be baled into said chamber. The baling plunger 11 is borne upon the compress head 12 which has journaled therein the flanged, un-threaded rear end of the compress screw 13, and bears securedly upon its forward face the compress screw casing 14, within which threadedly engages the right-hand thread of said compress screw. The thrust block 60 15 is rigidly secured by bolts 16 upon the top of the truck frame 1 and has turning within same the thrust journal 17, of the compress screw 13 exteriorly provided with integral thrust collars 18, which prevent 70 longitudinal motion of said compress screw, so that its revolution shall cause the alternate recession from and approach to said thrust block of said casing 14.

Referring to Figs. 1 and 3, the cone pinion 19, keyed upon the front end of the compress screw 13, is always simultaneously in mesh with the quick-return cone 20 keyed on the core shaft 21 and with the power cone 22 keyed upon the tube shaft 23, journaled in a vertical bore through the floor of the engine bed 24, through which bore it is prevented from gravitating by the hub of the power spur 25, keyed upon its upper end.

Referring to Figs. 3, 5 and 6, segmental 85 internal gears 26, interiorly secured upon the dependent track flange 27 of the turntable 28, engage at intervals with said power spur 25.

Referring to Figs. 3, 4 and 6, the quick-return spur 29 is in plane with and meshes into the teeth of the external segmental gears 30 borne upon segmental annular angles 31 inferiorly secured to the large gear-boss 32 made integrally upon the bottom of the turntable 28. The engine bed 24 is angularly fixed by adjustable pillar bolts as 33 engagedly secured between its end side and the truck frame 1 and bears channeled within its upper face the track-rolls 34, upon 100 which turns the track flange 27, as particularly shown in Fig. 3. The pivot pillar 35 dependent from the gear boss 32 turns within the socket collar 36 upon the balls 37, the upper half of whose circuit is countersunk within the base of said pivot pillar and the lower half of whose circuit is countersunk in the pivot pedestal 38. The king bolt 39 passes through axially registering bores in the pivot pedestal, pivot pillar, gear boss and turntable in such manner as to hold 105 the latter down upon its supporting anti-

friction ball and roller circuits and prevent angular inclination of the engine and gear train when in operation.

The engine 40 is bolted upon the turntable 28 so that its central vertical axis 5 axially registers with that of the king bolt 39. Said engine is of suitable gasoline type and is preferably provided with duplex flywheels 41-42 upon either end of its main shaft 43 at the outboard extremity of which is keyed the driving gear 44 which meshes with the annular gear 45 on the engine bed, so that the operation of the engine 40 will thereby cause its revolution with its attached turntable 28 and the consequent actuation of the gear train and hay-press. The pole sockets 46 are secured upon the top of the turntable 28 so as to permit the insertion of the movable draft pole 5 for 10 actuation of the press by animal power in the event of exhaustion of fuel or displacement of the engine.

The operation of our invention is as follows:

25 Referring to Figs. 1, 3 and 4, the clockwise rotation of the driving gear 44 upon the engine 40 causes a continuous anti-clockwise revolution of the turntable 28. In the position shown by these views the quick-return spur 29, actuated by one of the external segmental gears 30 is clockwise turning the core shaft 21 with its quick-return cone 20 meshing with the cone pinion 19 and by the latter's clockwise revolution 30 causing the longitudinally fixed compress screw 13 to withdraw by its casing 14 the baling plunger 11, in preparation for the reception through the hopper 10 into the chamber 9 of the hay to be baled.

35 40 As said anti-clockwise motion of the turntable 28 continues said external segmental gear 30 passes out of mesh with the quick-return spur 25, which thereby gives anti-clockwise revolution through the tube shaft 23 to the power cone 22 and to the attached compress screw 13, thus forcing its casing away from the thrust block 15, and compressing the hay in the baling chamber 9.

45 50 We so proportion the radii of our driving gear train, composed of said internal segmental gears, power spur, and power cone, with respect to the effective radius at which the latter meshes with the cone pinion, that the compressing revolution of the compress screw 13 is at twice the power and only half the speed of its retractive revolution in withdrawing said plunger; and we correspondingly so proportion the radii of the quick-return gear train, composed 55 of the external segmental gears, quick-return spur and quick-return cone, with respect to the extreme meshing radius of the cone pinion 19, as to cause the revolution of the screw in withdrawing the plunger at 60 twice the speed and half the power used in

compressing, which we claim to be an important economical practical feature in the operation of our hay-press.

The great simplicity and fewness of parts attained in the construction of our invention, by which all its automatic functions are performed without the use of ratchets or releasing mechanisms of any kind, with corresponding increase of durability and cheapness of manufacture, are only rendered possible by reason of the revolution of our actuating engine with its turntable, upon an axis perpendicular to but in plane with the shaft of the engine, and which therefore owes its efficiency in driving the 70 hay-press directly to its reaction against the annularly geared engine bed, as distinguished from boltings or connecting mechanisms of the ordinary kind.

This peculiarity of an engine capable of 75 revolution on an axis perpendicular to the horizontal plane of its bed we regard as the essential differentiation of our invention from all other hay-presses; and we do not wish to restrict ourselves to the particular 80 construction of gears and transmission mechanism utilized for taking the power from said engine as shown in the drawings, but reserve the right to vary that construction in any reasonable manner without departing from the spirit of our invention.

Having thus described our invention, we claim:

1. In a hay-press motor, a revoluble turntable mounted upon a pivot-column, having secured thereupon an engine provided with a driving gear, an angularly-fixed flanged engine-bed, concentrically surrounding said turntable, superficially provided with an annular gear adapted to mesh with said 100 crown driving gear in such manner as to reactively cause the revolution of said turntable with said engine, upon operation of the latter; and geared members adapted to transmit the power from said turntable to a member designed to be driven by said hay-press motor.

2. In a hay-press motor, a revoluble turntable, with a dependent flange, having interiorly secured thereon segmental internal gears; an engine secured upon said turntable provided with a driving gear on the drive shaft thereof adapted to revolvably actuate said turntable; an angularly-fixed engine-bed, having a continuous up-turned annular flange thereon concentrically surrounding said turntable, said flange being provided superficially with an annular gear adapted to mesh with said driving gear, so as to reactively revolve said turntable with said engine, upon operation of the latter; a geared member journaled upon said fixed engine bed, adapted to transmit the engine power from said turntable by meshing with said internal gears on the flanges thereof 115 120 125 130

to the member designed to be actuated by said motor; and geared members comprising a worm for transmitting the driving power from said geared member on said engine-bed to the member designed to be actuated by said hay-press motor.

3. In a hay-press motor, a revoluble turntable with a dependent flange supported on a central pivot-column; an engine having a 10 driving gear secured upon said revoluble turntable; an angularly-fixed flanged engine-bed, concentrically surrounding said turntable, provided superficially with an annular gear adapted by the meshing there- 15 of with said driving gear to impart reactive revolution to said turntable with said engine upon operation of the latter; a central segmental gear, secured inferiorily to said turntable upon said pivot column, adapted 20 to intermittently engage a quick-return pinion, mounted upon the upper end of a telescope-shaft journaled in said flanged engine-bed; a bevel gear upon the lower end of said telescope-shaft, adapted to mesh 25 with a bevel pinion, for causing quick re-

turn of the member to be driven by said motor; segmental internal gears on said dependent turntable flange; a power pinion, secured upon the upper end of the sleeve of said telescope-shaft in a plane below said 30 quick-return pinion, adapted to be intermittently driven by meshing with said internal gears; a power bevel gear secured upon the lower end of the sleeve of said telescope-shaft; a bevel pinion adapted to 35 mesh with said bevel gear; and, on the shaft of said bevel pinion, a screw coöperating with a sliding nut, adapted to transmit therethrough the power of said motor to the member designed to be actuated by 40 same.

Signed at Indianapolis, in the county of Marion and State of Indiana, this 7th day of September, 1912.

RAYMOND C. MOTT.
JESSE ALEXANDER.
